THERMOSTAT FOR COOKING APPLIANCES

John E. Reed, Glen Ellyn, Ill., assignor to Sunbeam Corporation, Chicago, Ill., a corporation of Illinois

Filed Apr. 27, 1961, Ser. No. 64,924

Term of patent 14 years

(Cl. D26—13)

FIG. 1 is a top perspective view of a thermostat for cooking appliances embodying my new design;

FIG. 2 is an enlarged top plan view thereof;

FIG. 3 is an enlarged side elevational view thereof;

FIG. 4 is an enlarged front end elevational view thereof;

FIG. 5 is an enlarged rear end elevational view thereof; and

FIG. 6 is an enlarged bottom plan view thereof.

The dominate features of the design reside in those portions shown in solid lines.

I claim:

The ornamental design for a thermostat for cooking appliances, substantially as shown and described.
